GOVERNING SYSTEM FOR DIESEL ENGINES WITH ARRANGEMENTS TO
WORK WITH INCREASED ADMISSION PRESSURE (SUPERCHARGING)

Filed Jan. 29, 1926

UNITED STATES PATENT OFFICE.

KURT SCHMIDT, OF COLOGNE-HOLWEIDE, GERMANY, ASSIGNOR TO MOTORENFABRIK DEUTZ, AKTIENGESELLSCHAFT, OF COLOGNE-DEUTZ, GERMANY.

GOVERNING SYSTEM FOR DIESEL ENGINES WITH ARRANGEMENTS TO WORK WITH INCREASED ADMISSION PRESSURE (SUPERCHARGING).

Application filed January 29, 1926, Serial No. 84,638, and in Germany December 10, 1925.

The present invention relates to a system of governing for Diesel-engines which are to run occasionally "supercharged" which means, that both the fuel charge and the air-pressure at the beginning of compression are increased above the values possible in ordinary working. This can be accomplished either by admitting air of increased or by introducing an additional charge of air of higher pressure when suction stroke or scavenging are completed and done in the ordinary way with air of atmospheric pressure. Higher initial pressures of compression result of course in increased final compression pressures.

If the timing of the beginning of fuel injection in relation to the position of the engine crank remains as in ordinary working, the final ignition pressure can easily become unduly high and the resulting strains may endanger the engine.

The invention provides for means to control the timing of the beginning of injection in such a way, that whenever the engine is to work with supercharged suction air, injection is delayed. The increase from final compression pressure to maximum ignition pressure is thereby reduced and the arrangement can be such, that when working with supercharged air the maximum ignition pressure is not greater than in ordinary working.

The diagrams show two ways to accomplish this end:

Fig. 1 is a diagrammatic view of one embodiment of the invention for accomplishing the desired result.

Fig. 2 is a diagrammatic representation similar to Fig. 1 and with the parts in a different position.

Fig. 3 is a diagrammatic representation of another embodiment of the invention with the parts in one position.

Fig. 4 is a diagrammatic representation similar to Fig. 3, but with the parts in another position, and

Fig. 5 shows the governor for operating the cam *c* in both embodiments of the invention.

In Figs. 1 and 2 *a* is the fuel-oil pump, *b* the camshaft carrying cam *c*, *d* the air-pump, which "supercharges" the air for the working cylinder. The delivery of pump *d* can be regulated by a valve *d* in the bye-pass *e*. To alter the time of injection according to

the rate of supercharging a lever "f" is provided, which rests on a fixed support at "p". The free end of this lever limits the down stroke of the fuel pump-plunger; the other end can turn on the eccentric disc "g". By operating lever "h" the position of the centre of *g* can be altered by hand so that the pump-plunger is lifted off the cam-disc, and the play between cam-disc and roller is increased which results in delaying the beginning of the useful stroke of the fuel-pump.

Lever *h* is connected to the bye-pass valve *d'* of the supercharging pump by rod *i*. In the position of Fig. 1 lever "f" does not interfere with the working of the fuel-pump at all and the system works without supercharging, the working cylinder filling with air of atmospheric pressure. When the engine is to run supercharged, lever *h* is gradually moved over from left to right in the position of Fig. 2. The play between cam-disc and roller is thereby increased in the same proportion as the valve *d'* throttles the passage *e* and the timing of injection is adjusted so as to delay it the more, the higher the rate of supercharging. In the present case the quantity of injected fuel is regulated through the oblique fuel-cam *c* being displaced axially by the action of the governor *g'*.

Figs. 3 and 4 show a different arrangement in connection with engines, in which the quantity of fuel is regulated by an overflow-valve, which may be the same as the suction valve *m*. This overflow-valve can be opened by the action of rod *n*, which is linked to lever *f*; lever *f* is situated on an eccentric *l*, the position of which relative to its shaft is subject to the action of the governor through lever *k*. Below lever *f* is an eccentric *g*, which is adjusted from the handlever *h* with the aid of a rod *i* according to the position of the throttling valve in passage *e*. In the position shown in Fig. 3 the system works without supercharging, the play between the fuel pump plunger and the cam-disc being a minimum. Fig. 4 shows the position of parts when running supercharged; the play between fuel pump and disc being increased. In this case too the injection is delayed when the rate of supercharging increases. Simultaneously with this delaying the effective lift of the fuel-pump is reduced, but as soon as the speed of the engine diminishes in consequence, the governor *g'* adjusts from the

eccentric *7* the quantity of fuel in proportion to the load.

I claim as my invention:

1. In an internal combustion engine, in combination, fuel injection means; operating means therefor; cooperating means adjustable to vary the time of initiation of the fuel injection; air supercharging means and means to render the same operative; and controlling means to actuate said last named means to render said air supercharging means operative and to adjust said cooperating means to retard the time of initiation of the fuel injection.
2. In an internal combustion engine, in combination, fuel injection means; operating means therefor; cooperating means adjustable to vary the time of initiation of the fuel injection; air supercharging means and means to render the same operative; controlling means to actuate said last named means to render said supercharging means operative and to adjust said cooperating means to retard the time of initiation of the fuel injection; and governing means for said fuel injection operating means to maintain automatically the amount of fuel injection in accordance with the engine load.
3. In an internal combustion engine, in combination, fuel injection means; operating means therefor; means to supply air of higher than atmospheric pressure to the engine; controlling means; and means actuated by said controlling means to retard the time of initiating of the fuel injection and to increase the amount of air of higher than atmospheric pressure supplied to the engine.
4. In an internal combustion engine, in combination, fuel injection means; operating means therefor; means to supply air of higher than atmospheric pressure to the engine; manually operable controlling means; and means actuated by said manually operable controlling means to retard the time of initiation of the fuel injection and to increase the amount of air of higher than atmospheric pressure supplied to the engine.

5. In an internal combustion engine, in combination, fuel injection means; operating means therefor; means to supply air of higher than atmospheric pressure to the engine; manually operable controlling means; and means actuated by said manually operable controlling means to vary the time of initiation of the fuel injection and the amount of air of higher than atmospheric pressure supplied to the engine.

6. In an internal combustion engine, in combination, fuel injection means; operating means therefor; means to supply air of higher than atmospheric pressure to the engine; controlling means, and means actuated by said controlling means to retard the time of initiation of the fuel injection and to render operative said means to supply air of higher than atmospheric pressure to the engine.

7. In an internal combustion engine, in combination, fuel injection means; operating means therefor; means to supply air of higher than atmospheric pressure to the engine; manually operable controlling means, and means actuated by said manually operable controlling means to retard the time of initiation of the fuel injection and to render operative said means to supply air of higher than atmospheric pressure to the engine.

8. In an internal combustion engine, in combination, fuel injection means; operating means therefor controllable to vary the amount of fuel injected; means automatically to control said fuel injection means so as always to inject the amount of fuel in accordance with the load on the engine; means to supply air of higher than atmospheric pressure to the engine; a manually operable controlling member; and means actuated by said controlling member to retard the time of initiation of the fuel injection and to render operative said means to supply air of higher than atmospheric pressure to the engine.

In testimony whereof I have signed my name to this specification.

KURT SCHMIDT.
